No. 658,453.

Patented Sept. 25, 1900.

H. C. MONTGOMERY.

FLUSHING APPARATUS FOR CLOSETS, &c.

(Application filed Feb. 15, 1900.)

(No Model.)

UNITED STATES PATENT OFFICE.

HARRY C. MONTGOMERY, OF CLEVELAND, OHIO.

FLUSHING APPARATUS FOR CLOSETS, &c.

SPECIFICATION forming part of Letters Patent No. 658,453, dated September 25, 1900.

Application filed February 15, 1900. Serial No. 5,342. (No model.)

To all whom it may concern:

Be it known that I, HARRY C. MONTGOMERY, a citizen of the United States, residing at Cleveland, in the county of Cuyahoga and State of Ohio, have invented certain new and useful Improvements in Flushing Apparatus for Closets, &c., of which the following is a specification.

My invention relates to means for flushing closets, &c.; and the improvement consists in the construction of an apparatus whereby controllable quantities of water are admitted to the bowls of said closets for the purpose of rinsing same.

15 The object of my improvement is to render said apparatus extremely simple in point of application and manipulation, sensitive and efficient in operation, reliable and durable in point of construction, and ornamental in appearance. I attain this object in an article constructed substantially as shown in the accompanying drawings, in which—

20 Figure 1 represents a vertical sectional view of said apparatus, and Fig. 2 is a transverse sectional view on line XX. (See Fig. 1.)

25 Like letters of reference denote like parts in the drawings and specification.

Substantially the apparatus consists of a casing A, a valve B, combined with a piston C and rod D, a bonnet E, and lever F. The casing A is adapted for pipe connection at its inlet a and outlet b. Provided in open relation with the inlet a is an internal cylinder c, of which the lower terminal c' serves in the 30 nature of a seat for the valve B, while the upper branch c² constitutes the cylinder proper for the piston C. The upper part of said casing is preferably screw-threaded for reception of the bonnet E, above mentioned.

35 For the valve B, I prefer the employment of suitable material other than metallic, so that at all times without noise a liquid-tight seating can be effected. Said valve is secured to the lower terminal of rod D by an adjustable screw-nut connection. About the middle portion of rod D an adjustable collar connection is formed for reception of the cup-washer d, which, in conjunction with the collars e e, serves in the nature of the piston C, above 40 referred to. Close at the upper terminal of said rod is a slot f, into which extends the short arm of the lever F, presently described.

The bonnet E serves the triple purpose—namely, that of closing up the casing A, of guiding the rod D, and of supporting the lever F. The connection with the casing is effected in the nature of a screw-joint, as previously stated, a guide for the rod is had within the neck g, and a support for the lever is had by and between the lugs h h and 45 pin i. (See Figs. 1 and 2.) The short arm j of the lever is rounded to accommodate an easy motion of the rod, and the long arm of said lever is provided with a weight k, which can be adjusted to suit conditions. The pin 50 i forms the fulcrum for the lever F, and the former may have connection with the lugs h h in any approved manner.

In its application this apparatus is placed in such relation to the bowl of closets as to 55 enable a most convenient manipulation of the lever. The outlet b is connected with the bowl, while to the inlet a water-supply pipe is attached of suitable size to insure an effectual rinsing or flushing of the bowl when 60 and while the valve is opened. Simply by lifting the lever the valve B can be opened for the water to rush into the bowl, whereupon said lever is left free to return to its 65 normal position, in which instance the valve 65 is held closed. It is merely a matter of adjustment of the weight and a certain proportioning of the diameter of the piston in relation to the valve which enables one to regulate the closing tendency of the valve. With 70 either the adjustment of the weight or a certain piston area counteracting the pressure upon the valve a more or less swift automatic closing action can be effected of and 75 for said valve.

In or with a flush-controller of the above description no stuffing-box is needed. Consequently the annoyance which is usually experienced with stuffing-boxes is eliminated.

The casing A not only excludes splashing, 80 but since it ordinarily does not come in contact with the water there will be no sweating experienced on the outside of the casing in case the supply-water is colder than the surrounding atmosphere.

85 What I claim, and desire to secure by Letters Patent, is—

90 A flushing apparatus for closets &c., comprising the combination of a casing having

an internal cylinder with inlet extending through the side of said casing; the outlet being formed in or with the lower terminal thereof, and the top being inclosed by a bonnet with tubular neck, a valve, piston and rod combined, the said valve controlling the lower face of said cylinder, the piston fitting the cylinder above its inlet and the rod being guided in said bonnet-neck, and a lever

equipped, supported and connected for closing said valve all constructed and arranged substantially as and for the purpose set forth.

In testimony whereof I affix my signature in presence of two witnesses.

HARRY C. MONTGOMERY.

Witnesses:

B. F. EIBLER,
JAMES MATHERS.
